ROLPH J. LACKNER, OF OZONE PARK, NEW YORK, ASSIGNOR TO LACKNER PRODUCTS CORPORATION, OF BROOKLYN, NEW YORK, A CORPORATION OF DELAWARE

REFLECTOR AND TRAFFIC SIGNAL

Application filed April 5, 1928. Serial No. 267,619.

This invention relates to a combined reflector and traffic signal, and one object of the invention is to provide a device of this character which will serve as a reflector to direct light downwardly upon a roadway and also serve as a traffic signal.

Another object of the invention is to provide a device of this character including a reflector and lens carrier suspended from the reflector and permitted to be adjusted circumferentially thereof and secured in set positions.

Another object of the invention is to so connect the lens carriers with the reflector that portions of the reflector to which the carriers are secured may serve to retain lenses in engagement with the carriers and prevent them from accidentally slipping out of place.

The invention is illustrated in the accompanying drawing, wherein

Figure 1 is a view in side elevation showing the improved reflector and traffic signal applied to an overhead light of a conventional construction;

Fig. 2 is a sectional view taken on the line 2—2 of Fig. 1;

Fig. 3 is a sectional view taken on the line 3—3 of Fig. 1;

Fig. 4 is a perspective view of one of the lens carriers, and

Fig. 5 is a side elevation illustrating a modified construction.

The reflector, which is indicated by the numeral 1, is formed of material which is strong and durable but at the same time light in weight and in the preferred construction aluminum is employed, although other materials may be substituted. This reflector is formed with a centrally located upstanding neck 2 of a conventional formation so that it may be secured to an overhead lamp socket 3 and support the reflector beneath the socket in radiating relation thereto. About its periphery the shield or reflector is formed with a depending marginal flange 4 having openings 5 formed therein in spaced relation to each other circumferentially of the flange and preferably four openings are provided so that the securing bolts 6 which are passed through the openings will be spaced to provide pairs

disposed in opposed relation to each other, as shown in Fig. 2. Since the shield or reflector is suspended from the lamp socket in radiating relation thereto, as shown in Fig. 1, it will be readily seen that, when a bulb or equivalent lamp carried by the socket is illuminated, light from bulb will be directed downwardly in order that a roadway over which the light is placed may be well illuminated.

The lens carriers which are supported by the reflector are of a duplicate construction and arranged in pairs disposed in opposed relation to each other. The lens carriers have been indicated in general by the numerals 7 and 8 and in the preferred arrangement the lenses 9 supported by the carriers 7 are red and the corresponding lenses supported by the carriers 8 are green, but it will be understood that the lens may be of any color desired according to the uses to which the signals are to be put. Each of the lens carriers consists of a metal casting 10 of a ring-like formation but having its upper corner portions 11 extended, as shown in Figs. 4 and 5, and carrying rearwardly extending side flanges 12 which terminate in spaced relation to the lower end of the casting and decreases in depth towards their lower ends, as clearly shown in Figs. 1 and 3. An up-

standing attaching lip 13 which is curved longitudinally extends transversely of the carrier with its intermediate portion flush with the outer surface thereof and its end portions curved rearwardly and joined to the side flanges. Webs 14 are provided in front of the rearwardly curved portions of the lip and serve as strengthening means and also define shoulders. The arc of the lip conforms to the curvature of the circular flange 4 and, therefore, the lip may have close fitting engagement with the inner surface of the flange. The lip of each lens carrier is formed with a longitudinally extending slot 15 so spaced from its upper and lower edges that, when the lens carriers are applied to the reflector, the openings 5 will register with the slots and the bolts may be passed through the slots, as shown in Fig. 2. By an inspection of this figure, it will be seen that after the

bolts have been passed through the slots of the lens carriers and openings in the depending flange of the reflector the lens carriers may be adjusted circumferentially of the reflector within the limits of the slots and, therefore, the reflectors may be disposed in opposed relation to each other if the openings 5 are not properly spaced from each other and when the securing nuts 16 of the bolts are tightened the lens carriers will be securely held in set positions and prevented from moving out of desired relation to each other. It should also be noted that since the lips of the lens carriers are disposed against the inner surface of the flange this flange will bear against the webs or shoulders 14 and prevent the lens carriers from tilting out of a vertical position.

In order to support the lenses 9 each of the carriers is formed with outwardly extending lens-engaging members 17 having lips at their outer ends to overlap the marginal portions of the lenses and between the hook-shaped lens-engaging members 17 are provided inwardly extending lips 18 which engage the inner surfaces of the marginal portions of the lenses. Therefore, the inner and outer surfaces of the marginal portions of the lenses will be engaged and the lenses well supported. The lenses are of such size that their upper portions terminate substantially flush with the lower edge of the lip 13 and, therefore, when the lens carriers are applied to the reflector, the lower edge of the flange will engage the lenses, as shown in Figs. 1 and 3, and serve very effectively to prevent the lenses from being accidentally jolted out of the carriers if the light or its support should be accidentally struck by a vehicle. I have, therefore, provided a combined light reflector and traffic signal which will serve very effectively to reflect light down upon a roadway and also serve as traffic indicator. It will be understood that, when in use, a pair of companion lights will be erected at a cross-road with the green lenses of one reflector disposed at right angles to the green lenses of the reflector for the second light.

In Fig. 5, the lens carriers are of the same construction, as shown in Figs. 1 through 4, but instead of being applied to a reflector they have been connected with a carrier having a central portion 19 adapted to be connected with the light socket 3 and arms 20 which radiate from the central portion. In the preferred construction, four arms are provided and these arms have down-turned free-ends, as shown at 21, each of which is formed with an opening 22. The upstanding lips of the lens carriers are disposed against the inner surfaces of the down-turned end portions of the arms 20 and when the securing bolts are passed through the slots 15 of the lips and openings 22, the lens carriers will be firmly secured with the ends of the arms engaging

the lens and serving to securely retain the lenses in the carriers.

Having thus described the invention, I claim:

1. In a traffic signal, a shield, means for connecting said shield with an overhead light carrier, said shield having a depending flange, a lens carrier disposed in depending relation to said shield and having an attaching lip at its upper end fitting against the inner surface of said flange, a lens supported by said carrier with its upper portion disposed beneath the flange whereby the flange serves to retain the lens in engagement with the carrier, and a fastener securing the lip of the lens carrier to said flange. 70

2. In a traffic signal, a shield, means for connecting said shield with an overhead light carrier, said shield having a depending flange, lens carriers disposed in depending relation to said shield and having attaching lips at their upper ends fitting against the inner surface of said flange, lenses supported by said carriers with their upper portions disposed beneath the flange whereby the flange serves to retain the lenses in engagement with the carriers, the lip of each carrier having a slot extending circumferentially of the flange, and bolts passed through the slots and flange to releasably secure the carriers to the flange, the carriers being adjustable circumferentially of the shield when the bolts are loosened. 85

3. In a traffic signal, a shield, means for connecting said shield with an overhead light carrier, said shield having its outer margin provided with a depending flange, lens carriers disposed in depending relation to said shield and having attaching lips at their upper ends fitting against the inner surface of said flange, lenses supported by said carriers with their upper portions disposed beneath the flange whereby the flange serves to retain the lenses in engagement with the carriers, the flange and lips of the carriers being formed with registering slots and openings and bolts passed through the slots and openings to releasably secure the carriers, the carriers being adjustable circumferentially of the shield within the limits of the slots when the bolts are loosened. 100

4. In a traffic signal, a light shield, means for connecting said shield with a light socket, said shield having its outer margin provided with a depending flange formed with circumferentially spaced openings, fasteners passed through said openings, and lens carrying frames disposed in depending relation to said flange and each having an upstanding lip across its upper end to bear against the inner face of said flange and shoulders projecting forwardly from the lower edge of its lip to engage the lower edge of the flange, the lips of said frames having transverse slots formed therein through which the fas- 115

teners pass whereby the frames may be adjusted circumferentially of the shield when the fasteners are loosened.

5. In a traffic signal, a light shield, means for connecting said shield with a light socket, said shield having its outer margin provided with a depending flange formed with circumferentially spaced openings, fasteners passed through said openings, and lens carrying frames disposed in depending relation to said flange and each consisting of a body defining an opening to be covered by a lens, means to support a lens in covering relation to the opening, the upper portion of the body being provided with rearwardly extending side flanges, a longitudinally curved lip projecting upwardly with its intermediate portion joined to the body and its end portions extending rearwardly and joined to said flanges, webs being provided between the body and rearwardly curved portions of the lip and constituting ledges to engage beneath the flange of said shield when the lip is disposed against the inner surface of the flange, the lips of said frames having slots formed therein transversely of the frames and through which the fasteners pass whereby the frames may be adjusted circumferentially of the shield when the fasteners are loosened.

In testimony whereof I affix my signature.
ROLPH J. LACKNER. [L. S.]
